WILLIAM K. RAIRIGH, OF RURAL VALLEY, PENNSYLVANIA.

Letters Patent No. 82,986, dated October 13, 1868.

IMPROVED CLAMP FOR SADDLERS, &c.

The Schedule referred to in these Letters Patent and making part of the same.

To whom it may concern:

Be it known that I, WILLIAM K. RAIRIGH, of Rural Valley, in the county of Armstrong, and State of Pennsylvania, have, as I believe, invented new and useful Improvements in Clamps for Saddlers and Shoemakers; and I do hereby declare the following to be a full and exact description of the same, reference being had to the drawings that accompany and form a part of these specifications.

Figure 1 is a view of the clamp closed.

Figure 2, view of the clamp with the jaws open.
A, the jaws of the clamp.

B, a shaft lying between the two jaws, as in fig. 2.
C, a small chamber, in arrangement as in fig. 2.
D, a ratchet-wheel, which, together with the working-crank E, is fixed firmly on the shaft B.

e, a pawl, the lower end of which, at i, catches into the ratchet of the wheel D.

g, a spring, whose force is so exerted as to keep the pawl to the ratchet.

h, upper end of the pawl e, and is extended quite through an opening therefor in the rim of the chamber C, as may be seen in fig. 2.

j, pinion on which the pawl e turns.

k, a strap, one end attached to the shaft B; the other to the hinged jaw of the clamp.

l, a spring, whose force throws the jaws A apart when desired.

My invention relates to the manner of holding the jaws together when used, and the device for relieving them when it is desired that they should open.

My device for this is the chamber C, ratchet D, pawl e, spring g, and crank E, arranged as set forth. I do not claim the spring l nor the strap k.

In use, to bring the jaws A together, the ratchet-wheel D is turned; the pawl e holding it at any tension given it. The strap k being wound on the shaft B, draws the hinged jaw close, as required. To loosen the jaws, take hold of the extension, h, of the pawl e, and draw it upwards until the ratchet is relieved, when the force of the spring l forces them apart.

What I claim as of my invention, and desire to secure by Letters Patent, is—

The shaft B, with its ratchet D, the chamber C, pawl e, and spring g, when arranged upon and made to operate the jaws of a clamp, substantially as and for the purposes specified.

In testimony whereof, I have signed my name to this specification in the presence of two subscribing witnesses.

WM. K. RAIRIGH.
